US00D701854S

(12) **United States Design Patent**
Katsumata et al.

(10) **Patent No.:** US D701,854 S
(45) **Date of Patent:** ** Apr. 1, 2014

(54) **EARPHONE**

(71) Applicant: **Sony Corporation**, Tokyo (JP)

(72) Inventors: **Jun Katsumata**, Tokyo (JP); **So Morimoto**, Tokyo (JP); **Sohei Kitayama**, Tokyo (JP)

(73) Assignee: **Sony Corporation**, Tokyo (JP)

(**) Term: **14 Years**

(21) Appl. No.: **29/436,242**

(22) Filed: **Nov. 2, 2012**

Related U.S. Application Data

(63) Continuation of application No. 29/371,962, filed on Feb. 24, 2012, now Pat. No. Des. 670,274.

(57) **CLAIM**

The ornamental design for an earphone, as shown and described.

DESCRIPTION

FIG. 1 is a rear, left perspective view of a first embodiment of an earphone showing our new design;

FIG. 2 is a rear elevational view thereof;

FIG. 3 is a left side elevational view thereof;

FIG. 4 is a right side elevational view thereof; and

FIG. 5 is a top plan view thereof.

FIG. 6 is a rear, left perspective view of a second embodiment of an earphone showing our new design;

FIG. 7 is a rear elevational view thereof;

FIG. 8 is a left side elevational view thereof;

FIG. 9 is a right side elevational view thereof;

FIG. 10 is a top plan view thereof; and

FIG. 11 is a bottom plan view thereof.

FIG. 12 is a rear, left perspective view of a third embodiment of an earphone showing our new design;

FIG. 13 is a rear elevational view thereof;

FIG. 14 is a left side elevational view thereof;

FIG. 15 is a right side elevational view thereof; and,

FIG. 16 is a top plan view thereof.

The portions indicated in broken lines are for illustrative purposes only and form no part of the claimed design.

1 Claim, 15 Drawing Sheets
